UNITED STATES PATENT OFFICE

2,454,619

WINDOW SASH CONTROL

Jonas A. Swenson, Springfield, S. Dak.

Application December 8, 1945, Serial No. 633,884

2 Claims. (Cl. 26—54)

1

My invention as described herein, and illustrated in the accompanying drawings, consists of a window sash support, an object of which is to provide frictional means for holding a sash in raised position.

Another object of my invention is to provide spring controlled means for holding a sash tight against a parting strip.

A further object of this invention is to provide a spring controlled retainer strip for a window frame.

A primary object of my invention is the provision of means in a window frame for holding a sash tight against a parting strip, said means being also adapted to frictionally hold a sash in any raised position.

Other features and advantages will become more readily apparent from the following description and the accompanying illustrative drawings in which:

Figure 1 is a vertical, sectional view of a window embracing my invention,

Figure 2 is a sectional view on line 2—2 thereof,

Figure 3 is an elevational view of the inner side of a retainer strip,

Figure 4 is an enlarged sectional view on line 4—4 of Figure 1,

Figure 5 is a transverse sectional view on line 5—5 of Figure 1,

Figure 6 is an enlarged sectional view on line 6—6 of Figure 1, and

Figure 7 is a detail of a cup.

While one embodiment of my invention is illustrated in the above referred to drawings, it is to be understood that they are merely for the purpose of illustration and that various changes in construction may be resorted to in the course of manufacture in order that the invention may be utilized to the best advantage according to circumstances which may arise, without in any way departing from the spirit and intention of my device, which is to be limited only in accordance with the appended claims. And while I have stated the primary field of utility of my invention it remains obvious that it may be employed in any other capacity wherein it may be found applicable.

In the accompanying drawings, and in the following specification, the same reference characters are used to designate the same parts and elements throughout and in which 10 refers to my invention and 11 indicates a window frame having a parting strip 12 for separating the sashes 13 and 14, the latter being slidable in a glyph or channel 15, formed by the strip 12 and

2

a retainer strip 16. A conventional blind strip and the parting strip 12 retain the sash 13 in the window frame. The strip 16 is provided with several longitudinal slots 17, 18, and 19, in its rear wall 20, separated by walls 21 and 22, through which are bores. Strung through the slots and bores is a piano wire spring 24, the ends 25 and 26, of which are secured in the terminal bores 27 and 28 of the strip 16.

From the outer surface 29 of strip 16, are several horizontal relatively large bores 30, 31 and 32, extending to the slots 17, 18, and 19, in which latter bores are seated countersunk cups 33, 34, and 35, each having a longitudinal horizontal slot 36. Projecting through bores 30, 31, and 32, and slots 17, 18, and 19, and threaded into the wall 37, are screws 38, the heads of which seat within said cups 33, 34, and 35 and straddle the slots 36, whereby the strip is secured to the wall 37. All of the said screws pass to the outer side 41 of the spring 24, whereby the strip 16 will normally be spring pressed against the stile 42 of a window sash 43, thus at all times forcing the sash against the parting strip 12. The tension of the spring 24 is such that the sash 14 will be held in any raised position, but not such as to prevent moving the sash up and down. Stops 44 and 45, are attached to the lower end 47 of the wall 37, as well as the upper end of the same wall to limit the in movement of the strip 16, when the upper or lower ends 48 and 49, of the strip are free, and cutouts 50 and 51 are provided in the upper and lower ends of the strips to receive the stops 44 and 45.

It is thought that persons skilled in the art to which the invention relates will be able to obtain a clear understanding of the invention after considering the description in connection with the drawings. Therefore, a more lengthy description is regarded as unnecessary.

Changes in shape, size and rearrangement of details and parts such as come within the purview of the invention claimed may be resorted to, in actual practice, if desired.

Having now described my invention, that which I claim as new and desire to procure by Letters Patent is:

1. The described device comprising a window frame, a parting strip therein and a movable retainer strip for a sash, said retainer strip having countersunk cups embedded therein, slots in said cups and disposed transversely of said retainer strip, screws inserted through said slots and into said frame so that said retainer strip may move toward said sash, a longitudinal spring

for urging the retainer strip against the sash, said spring being substantially coextensive in length with and carried within the retainer, the ends of the spring being secured to said retainer strip and intermediate portions of said spring contacting said screws so that the spring is stressed, and means for limiting the movement of the retainer.

2. The described device comprising a window frame, a parting strip therein and a movable retainer strip for a sash, said retainer strip having countersunk cups embedded therein, slots in said cups and disposed transversely of said retainer strip, screws inserted through said slots and into said frame so that said retainer strip may move toward said sash, a longitudinal spring for urging the retainer strip against the sash, said spring being substantially coextensive in

length with and carried within the retainer, the ends of the spring being secured to said retainer strip and intermediate portions of said spring contacting said screws so that the spring is stressed.
